FIG. 1 is a perspective view of a cap embodying the design of the present invention;

FIG. 2 is a side elevational view;

FIG. 3 is a top plan view;

FIG. 4 is a rear elevational view;

FIG. 5 is a front elevational view;

FIG. 6 is a perspective view of a cap design constituting a second embodiment of the present invention;

FIG. 7 is a side elevational view of the second embodiment;

FIG. 8 is a top plan view of the second embodiment;

FIG. 9 is a rear elevational view of the second embodiment;

FIG. 10 is a front elevational view of the second embodiment;

FIG. 11 is a perspective view of a cap design constituting a third embodiment of the present invention;

FIG. 12 is a side elevational view of the third embodiment;

FIG. 13 is a top plan view of the third embodiment;

FIG. 14 is a rear elevational view of the third embodiment;

FIG. 15 is a front elevational view of the third embodiment;

FIG. 16 is a perspective view of a cap design constituting a fourth embodiment of the present invention;

FIG. 17 is a side elevational view of the fourth embodiment;

FIG. 18 is a top plan view of the fourth embodiment;

FIG. 19 is a rear elevational view of the fourth embodiment; and

FIG. 20 is a front elevational view of the fourth embodiment.

For convenience of illustration, only parts of the knitted mask portions and outer bands have been shaded in the several views of the drawings. It is to be understood that these surfaces continue throughout the plane areas shown.

My design is characterized by the provision on a peaked ski cap of the type disclosed of the permanently attached, tubular knitted face mask and head covering depending

therefrom, and having an opening or openings in the front substantially as shown.

In the species of FIGURES 1-5, the design is specifically characterized by a single opening for the eyes in the knitted tubular face mask and head covering, and the provision of a knitted turn-down outer band or cuff secured to the sides of the cap body. The species of FIGURES 6-10 is specifically characterized by the provision of individual eye and mouth openings in the tubular knitted face mask and head covering, and by the provision of a knitted turn-down outer band or cuff secured to the sides of the cap body. The species of FIGURES 11-15 is specifically characterized by the provision of a single opening for the eyes in the tubular knitted face mask and head covering, and the species of FIGURES 16-20 is specifically characterized by the provision of individual eye and mouth openings in the knitted face mask and head covering.

This application is a continuation of my copending applications Serial Number D. 74,015, filed March 18, 1963, and Serial Number D. 74,171, filed March 28, 1963.

I claim:

The ornamental design for a cap, substantially as shown and described.
